Specification for Design.

Patented Aug. 9, 1921.

Application filed March 26, 1921. Serial No. 455,991. Term of patent 14 years.

To all whom it may concern:

Be it known that I, WILLIAM G. LERCH, a citizen of the United States, residing at Akron, in the county of Summit and State of Ohio, have invented a new, original, and ornamental Design for Tire-Treads, of which the following is a specification, reference being had to the accompanying drawings, forming a part thereof.

In the drawings, Figure 1, is a plan view showing the new design.

Fig. 2 is a transverse section through a tire, provided with the new design, on the line 2—2 of Fig. 1.

I claim:

The ornamental design for a tire tread, as shown.

WILLIAM G. LERCH.
